UNITED STATES PATENT OFFICE

145,195

DESIGN FOR A CHEST

Edwin L. Beckwith, Brookline, Mass., assignor to Beckwith Manufacturing Company, Dover,
N. H., a corporation of New Hampshire

Application October 12, 1945, Serial No. 122,793

Term of patent 14 years

(Cl. D58—12)

To all whom it may concern:

Be it known that I, Edwin L. Beckwith, a citizen of the United States, residing at Brookline, in the county of Norfolk and Commonwealth of Massachusetts, have invented a new, original, and ornamental Design for a Chest, of which the following is a specification, reference being had to the accompanying drawing, forming a part thereof, in which the figure is a view in perspective of a chest, showing my new design.

The end and side not shown are substantially the same as the front side and end respectively as shown.

I claim:

The ornamental design for a chest, substantially as shown and described.

EDWIN L. BECKWITH.
